UNITED STATES PATENT OFFICE.

JOHN S. NASH, OF CHICAGO, ILLINOIS.

TUMBLER-WASHER.

No. 917,887.

Specification of Letters Patent.

Patented April 13, 1909.

Application filed August 17, 1908. Serial No. 330,958.

To all whom it may concern:

Be it known that I, JOHN S. NASH, a citizen of the United States, and a resident of Chicago, in the county of Cook and State of Illinois, have invented certain new and useful Improvements in Tumbler-Washers, of which I do declare the following to be a full, clear, and exact description, reference being had to the accompanying drawing, forming 10 part of this specification.

The present invention has relation more particularly to that class of tumbler washers designed for washing tumblers used at soda water fountains, and the invention consists 15 in the features of novelty hereinafter described, illustrated in the accompanying drawing and particularly pointed out in the claims at the end of this specification.

Figure 1 is a view in central vertical section through a tumbler washer embodying my invention. Fig. 2 is a view in horizontal section on line 2—2 of Fig. 1. Fig. 3 is a view in central vertical section through parts shown in Fig. 1, but illustrating the valve 25 mechanism in closed position. Fig. 4 is an enlarged detail view in vertical section through the spray head or nozzle. Fig. 5 is a detail view showing the upper end of the conical distributor at the top of the spray 30 nozzle.

In the accompanying drawing, A designates the bowl or vessel that is adapted to set within an opening in the serving counter, or any other convenient location. The 35 lower end of the bowl A is suitably secured to the top of a coupling B that is provided with a passage b communicating with an opening in the bottom of the bowl A for the escape of water from the bowl, and is provided also 40 with an induction channel b' through which fresh water will be delivered for cleansing the tumbler.

Within the coupling B, which is preferably a suitable casting, is arranged an interiorly 45 threaded, vertical flange b² with which engages the correspondingly threaded lower end of a valve casing C, a packing ring b³ being preferably interposed between the lower end of the valve casing C and a shoulder that 50 is formed at the base of the annular flange b². As shown, the lower end of the valve casing C is interiorly threaded to receive a correspondingly threaded, perforated or open valve stem support D, through the openings

in which water will freely pass, as will presently appear. Through the hub of the valve stem support D passes the stem e of the valve E, this valve E being conical or furnished with a conical packing ring that will engage with a valve seat or shoulder c² upon 55 the interior of the valve casing C. The opening c³ above the valve seat c² is slightly larger than the cylindrical portion c⁵ of the valve stem immediately above the valve E, and above this portion c³ of the valve stem, the 60 stem is reduced as at e⁴ so as to allow for the free passage of the water through the valve seat when the valve is in open position, as illustrated in Fig. 1 of the drawing. The valve E is also slightly smaller in diameter 65 than the cylindrical portion c⁵ of the valve casing beneath the seat c² of the valve. A coil spring F that is interposed between the valve E and the hub of the valve stem guide D serves to normally hold the valve E against 70 its seat c² as clearly shown in Fig. 3 of the drawing.

A serious objection with valve mechanism heretofore employed in tumbler washers of this general type is, that when the tumbler is 75 suddenly lifted or closed quickly to cut off the flow of water, there is a tendency of the valve to pound or rebound upon its seat, thus producing a disagreeable noise. By forming the valve casing with a contracted cylindrical portion c⁵ beneath the valve seat, 80 through which the valve E shall pass as it approaches the seat c², the closing of the valve is more gradual and all danger of the pounding or rebounding of the valve and 85 water hammer in the pipes is avoided. And this is overcome in a measure, also, by providing the enlarged portion c³ of the valve stem, which portion enters the opening 90 through the valve seat c² as the valve closes 95 against its seat. In other words, the gradual restriction of the flow of water, as the valve is slowly seated, effectively, serves to prevent the pounding or rebounding of the valve when it reaches its seat. 100

The upper portion of the valve casing C is provided with threaded openings in which are fitted threaded ends of the angular spray tubes G, these spray tubes being preferably four in number and arranged to extend upwardly, as shown, adjacent the wall of the bowl A. Each of the spray tubes G is formed with a plurality of transverse, in-

clined slits *g* through which water will be projected in a thin film and in downward direction against the exterior of the tumbler *H* to be cleaned.

- 5 The upper end of the valve casing *C* is internally screw-threaded to receive the correspondingly threaded end of a cap *K* that is perforated to permit the tubular portion *E'* of the valve stem to slide freely therethrough.
- 10 This tubular portion *E'* of the valve stem is provided at its base with lateral channels *e* that communicate with a chamber at the upper end of the valve casing *C*. The top of the tubular extension *E'* of the valve stem is
- 15 screw-threaded to receive the threaded hub *m* of the tumbler support *M*, this support comprising a plurality of arms *m'* that are covered with rubber tubes *m''* or similar soft material, against which the edge of the
- 20 tumbler *H* will bear, as shown in Fig. 1 of the drawing. From the top of the hub *m* of the tumbler support projects the spray-head through which water will be delivered to cleanse the interior of the tumbler *H*. As
- 25 shown, this spray-head comprises a casing formed of a lower part *N* and an upper part *N'*, the lower part *N* having a tubular, contracted portion that is screw-threaded to engage the hub *m* of the tumbler support, and
- 30 the two parts *N* and *N'* are connected together by a threaded joint, as clearly shown in the drawing. Within the spray-head casing is mounted a distributor *P* that is provided with a plurality of open ended, spiral
- 35 channels *p* that will serve to impart a swirl to the water as it passes through the opening *n* in the cap or upper portion *N'* of the casing, and into this opening *n* preferably projects an extension *p'* that rises from the top of the
- 40 distributor *P*.
- When the washer is in normal or idle position, the parts will occupy the position shown in Fig. 3 of the drawing, at which time the valve *E* will serve to completely cut off the
- 45 flow of water. If, now, an inverted tumbler *H* be placed upon the tumbler support *M* and be pressed downward so as to compress the coil spring *F* and force the valve *E* and parts to the position shown in Fig. 1 of the drawing, the water will flow through the valve
- 50 casing and will be distributed by the spray tubes *G* over the exterior of the tumbler. At the same time the water will pass through the spray-head or nozzle and, by reason of
- 55 the spiral channels of the distributor *P*, will be caused to pass in a swirling film against the interior of the tumbler, and this action will continue so long as the tumbler is held in the depressed position shown in Fig. 1.
- 60 When the pressure on the tumbler is relieved, the parts will resume the normal position shown in Fig. 3 of the drawing. By imparting a swirling movement to the water issuing from the spray-head or nozzle, a
- 65 much more thorough cleansing of the inter-

rior of the tumbler is effected, not only because of the more complete and uniform distribution of the water over the interior of the tumbler, but also because of its being thrown in a spiral course against and around the interior of the tumbler. So, also, when the valve is allowed to close in order to cut off the flow of water through the valve casing, the action is such that all pounding or rebounding of the valve is avoided.

75 While I describe what I regard as the preferred form of my invention, I do not wish the invention to be understood as restricted to the precise details of construction above set forth, as these may be varied without departure from the scope of the invention.

80 Having thus described my invention, what I claim as new, and desire to secure by Letters Patent, is:

1. A tumbler washer, comprising a valve 85 casing having a downwardly facing valve seat and a contracted chamber beneath said valve seat and a wider chamber communicating with and beneath said contracted chamber, a valve stem provided at its top with a tumbler support, a valve on said stem slightly smaller than said contracted chamber and arranged to pass from said chamber into said wider chamber, and a spring for forcing said valve toward its seat and means 90 leading from the valve casing for spraying a tumbler.

2. A tumbler washer comprising a valve casing provided with upper and lower water chambers, tubular spray arms connected to 100 said upper water chamber and arranged to spray the exterior of the tumbler to be washed, a downwardly facing valve seat at the base of said upper chamber, said casing having a contracted cylindrical chamber beneath said valve seat and above said lower water chamber, and a valve slightly smaller than said contracted chamber arranged to pass from the contracted chamber into said lower water chamber.

105 3. A tumbler washer comprising a valve casing provided with upper and lower water chambers and an intermediate, downwardly facing valve seat and a contracted chamber beneath said valve seat, tubular arms leading outwardly and upwardly from said upper water chamber and a valve arranged beneath said valve seat and provided with an upwardly extending tubular stem having a spray nozzle at its upper end.

110 4. A tumbler washer, comprising a valve casing having upper and lower water chambers and having a downwardly facing valve seat with an opening therethrough for the passage of water, a valve closing against said seat, and a valve stem therefor having at its top a tumbler support and provided immediately above the valve with an enlarged part slightly smaller than the opening of the valve seat and adapted to check the flow of

water as the valve approaches its seat and means leading from the valve casing for spraying a tumbler.

5. A tumbler washer, comprising a valve casing having upper and lower water chambers and an intermediate downwardly facing valve seat and a contracted chamber immediately beneath said valve seat, a valve slightly smaller than said contracted chamber, a valve stem carrying said valve and having its upwardly extending part provided with a tumbler support, said valve stem being also provided with an enlarged part slightly smaller than the opening of the 10 valve seat and adapted to check the flow of water as the valve approaches its seat and means leading from the valve casing for spraying a tumbler.

6. A tumbler washer comprising a chambered valve casing provided with means for directing a spray of water against the exterior of the tumbler to be washed, and provided with a valve seat, a spring actuated valve for closing against said valve seat a 20 spray nozzle having a central opening, and means therein adapted to deliver a swirling spray against the interior of the tumbler to be washed.

7. A tumbler washer comprising a valve casing having upper and lower water chambers and an intermediate valve seat, means connected to said upper water chamber for distributing water over the exterior of the tumbler to be washed, a valve arranged 30 within said casing and provided with a tubular stem communicating with said upper water chamber and extending through the top thereof, and a spray nozzle carried by the upper end of said tubular valve stem 35 and provided with interior means for projecting a swirling spray of water against the interior surface of the tumbler to be washed.

8. A tumbler washer comprising a valve casing having upper and lower water chambers and an intermediate valve seat, means connected to said upper water chamber for distributing water over the exterior of the tumbler to be washed, a valve arranged 40 within said casing and provided with a tubular stem communicating with said upper water chamber and extending through the top thereof, and a spray nozzle carried by the upper end of said tubular valve sleeve 45 and provided with an inclosed distributor 50 having spiral channels for imparting a

swirling motion to the spray of water to be projected against the interior surface of the tumbler to be washed.

9. A tumbler washer comprising a valve casing having upper and lower water chambers and an intermediate valve seat, means connected to said upper water chamber for distributing water over the exterior of the tumbler to be washed, a valve arranged 60 within said casing and provided with a tubular stem communicating with said upper water chamber and extending through the top thereof, and a spray nozzle carried by the upper end of said tubular valve stem and provided with an inclosed distributor having 65 spiral channels upon its exterior for imparting a swirling motion to the spray of water to be delivered against the interior of the tumbler to be washed.

10. A tumbler washer comprising a valve 75 casing having upper and lower water chambers and an intermediate valve seat, means connected to said upper water chamber for distributing water over the exterior of the tumbler to be washed, a valve arranged 80 within said casing and provided with a tubular stem communicating with said upper water chamber and extending through the top thereof, and a spray nozzle carried by 85 the upper end of said tubular valve stem and provided with a top having a central opening and a distributor provided with spiral channels beneath said opening and with an upwardly extending part projecting 90 into the opening of said top.

11. A tumbler washer comprising a valve casing having upper and lower water chambers and an intermediate valve seat, means connected to said upper water chamber for distributing water over the exterior of the tumbler to be washed, a valve arranged 95 within said casing and provided with a tubular stem projecting through the top of the casing, an expanded chamber at the top of said valve stem having an unobstructed top 10 and an opening and provided with interior means for delivering a swirling spray against the interior of the tumbler to be washed, and a tumbler support carried by the valve stem below its upper end.
